UNITED STATES PATENT OFFICE.

FRANK MILHENING, OF CHICAGO, ILLINOIS, ASSIGNOR TO J. MILHENING, INC., OF CHICAGO, ILLINOIS, A CORPORATION OF ILLINOIS.

RING.

1,224,193.

Specification of Letters Patent.

Patented May 1, 1917.

Application filed May 18, 1916. Serial No. 98,326.

To all whom it may concern:

Be it known that I, FRANK MILHENING, a citizen of the United States, and a resident of the city of Chicago, county of Cook, and 5 State of Illinois, (whose post-office address is 135 South State street, Chicago,) have invented a new and useful Improvement in Rings, of which the following is a specification.

10 The object of my invention is to provide a composite ring such as a wedding ring, composed of two different metals, as gold and some other metal, such as platinum, and this ring may or may not be ornamented, as 15 desired. This invention is particularly adapted to wedding rings where it is the desire of the owner to have the ring provided with a permanent platinum finish or a finish of other metal. This object is 20 accomplished by my invention, as will more particularly hereinafter appear.

For a more particular description of this invention, reference is to be had to the accompanying drawings, forming a part here- 25 of, in which—

Figure 1 is a perspective view of a tube of another metal than that of which the ring is made with a dotted line indicating where it may be severed so as to provide an 30 annulus for a ring;

Fig. 2 is a sectional view showing an annulus about the ring and ready to be applied thereto;

Fig. 3 is a sectional view showing the 35 annulus applied about the ring; and

Fig. 4 is a large section showing a slightly modified construction.

Throughout the various views of the drawings, similar reference characters des- 40 ignate similar parts.

In this instance, we will assume that it is desired to provide a platinum finish on a gold ring. A platinum tube 1 of suitable diameter is severed at 2 so as to provide an 45 annulus 3 which may be placed about the

ring, which I have shown as an ordinary wedding ring 4, as shown in Fig. 2. After having been so placed, the annulus is spun about the ring until the exposed surface of the gold ring is covered with the platinum 50 and the inner surface of the ring which is next to the finger of the wearer is not disturbed, so that all monograms, initials or other writings which may appear thereon are preserved intact and not mutilated or 55 obliterated.

In the structure shown in Fig. 4, the ring 4 has grooves at its inner edge into which the edges 5 of the annulus 3 are forced, so as to make a tight joint and prevent all 60 possible tendency to disintegrate or separate from the ring 4. The platinum or other metal 3 is made thick enough to be engraved, ornamented or embellished as de- 65 sired.

While I have set forth that the metals combined in the ring mentioned herein are platinum and gold, it will be obvious that various kinds of metals may be utilized in the manner above stated, so I do not limit 70 my invention to the use of any specific metals.

While I have shown and described some embodiments of my invention, it is obvious that it is not restricted thereto, but is broad 75 enough to cover all structures that come within the scope of the annexed claim.

Having thus described my invention, what I claim is:

In a device of the class described, a ring 80 of one metal provided with grooves in its edges, an annulus of another metal spun over the outer side of said ring with its edges spaced apart and fitting said grooves whereby the inner side of said ring is left 85 uncovered.

Signed at the city of New York, county of New York, and State of New York, this 17th day of May, 1916.

FRANK MILHENING.
